This invention relates to processes for the permanent deformation of keratinous material and more particularly to the "permanent waving" of human hair, to aqueous solutions for use in the said processes and to processes for the production of the said solutions.

In the permanent deformation of hair, and more particularly in the reduction of the cystine bridges in keratin, it has previously been known to use reducing solutions of ammonium thioglycolate containing ammonium carbonate. The pH value of such solutions, which may vary between about 7.7 and 9, depends to a large extent upon their content of free ammonia and carbon dioxide.

These reducing solutions, which can be used around pH 8, have definite advantages over the previously employed solutions of ammonium thioglycolate lacking ammonium carbonate which have pH values between about 9.2 and 9.5. One advantage is the lower risk of damage to the hair caused by hydrolysis of the keratin, because the hydrolysis rate is lower at, say, pH 8 than at pH values above 9. Another advantage is that, in the case of sensitive skins, most of the irritations of the scalp and of the hands of the operator are substantially avoided using solutions of about pH 8. Further, solutions having lower pH values generally have much less objectionable odour than those, for example, having pH values above 9.2.

Nevertheless, reducing solutions of relatively low pH value do have certain disadvantages which render their use inconvenient. For example, their ability to impart a permanent curl to constrained hair is relatively low at about pH 8, so that it is necessary to prolong the duration of application, or to use a heating hood, or to increase the concentration of the reducing agent in the solution. Regardless of the method adopted, the waving operation becomes more difficult.

It has now been found that the aforesaid disadvantages may be obviated by replacing the ammonia, both in its function as a neutralising agent for the acid reducing agent and in the form of ammonium carbonate, by an organic base such as guanidine, monoethylamine, monoethanolamine, monoisopropanolamine, diethanolamine or morpholine.

According to a first feature of the present invention, therefore, an aqueous solution for use in effecting the permanent deformation of hair or other keratinous material comprises a salt of a mercaptocarboxylic acid with an organic base and a carbonate of an organic base, the pH value of the solution being from 7 to 9.

According to a further feature of the present invention a method of imparting a permanent deformation to hair or other keratinous material comprises constraining the material to a desired configuration, treating the constrained material at room temperature with an aqueous solution as just set forth and thereafter setting the configuration of the material by oxidation.

2

As mercaptocarboxylic acids there are preferably employed thioglycollic acid or thiolactic acid and these are preferably employed in concentrations from 0.3 to 1.5 mols per litre. The preferred pH value of the solution is from 7.5 to 8.5. The concentration of the carbonate of the organic base may advantageously vary between 0.1 and 1.5 mols per litre.

Various methods for the preparation of the solutions of the present invention may be employed. Thus, for example, it is possible exactly to neutralise a mercaptocarboxylic acid solution by means of an organic base and then to add the required quantity of the carbonate of an organic base. It is also possible to add to a solution of the acid a slight excess of the organic base over that required to neutralise the acid. The excess base may then be converted into its carbonate by introducing into the solution the necessary quantity of carbon dioxide through a distributing head. In either procedure the pH value of the solution can be adjusted to between 7 and 9 by regulating the quantity of carbon dioxide introduced.

The solutions obtained by carrying out the procedures indicated above are applied to hair or other keratinous material at room temperature by the method usually adopted in permanent waving with, for example, ammonium thioglycolate, i.e., in a first phase the locks of hair are impregnated with the waving solution, they are wound on curlers and each curler is then saturated with the solution which is allowed to act for 5 to 20 minutes, depending upon the nature of the hair. The hair is then rinsed and thereafter treated with an oxidising solution in accordance with the usual technique. There is thus obtained a springy curl which has good resistance to humidity and shampoos.

The following examples, which describe the preparation of cold waving solutions which may be used in the conventional manner indicated above, will serve to illustrate the invention:

Example I

40 A solution is prepared having the following composition:

	G.
Thioglycollic acid	8
Monoethanolamine	10
Water to make 100 cc.	

45 A current of CO₂ is slowly introduced into this solution through a distributing head until the solution has a pH of 8.2.

Example II

50 The following solution is prepared:

	G.
Thioglycollic acid	8
Morpholine	16
Water to make 100 cc.	

55 CO₂ is introduced until the solution has a pH value of 8.2.

Example III

60 The following solution is prepared:

	G.
Thioglycollic acid	8
Monoethanolamine	7.8
Water to make 100 cc.	

65 CO₂ is introduced until the solution has a pH value of 7.6.

3

Example IV

The following solution is prepared:

Thioglycollic acid	8	G.
Diethanolamine	21	5
Water to make 100 cc.		

CO₂ is introduced until the solution has a pH value of 8.2.

Example V

The following solution is prepared:

Thiolactic acid	9.2	G.
Monoisopropanolamine	14	
Water to make 100 cc.		

CO₂ is introduced until the solution has a pH value of 8.5.

Example VI

The following solution is prepared:

Thioglycollic acid	8	G.
Guanidine carbonate	8.5	
Water to make 100 cc.		

CO₂ is introduced until the solution has a pH value of 7.3.

Example VII

The following solution is prepared:

Thioglycollic acid	8	G.
Ethylamine	5.6	30
Morpholine	6	
Water to make 100 cc.		

CO₂ is introduced until the solution has a pH value of 8.2.

Example VIII

The following solution is prepared:

Thioglycollic acid	8	G.
Monoethanolamine	6.8	
Morpholine	6	
Water to make 100 cc.		

CO₂ is introduced until the solution has a pH value of 8.2.

Example IX

The following solution is prepared:

Thioglycollic acid	8	G.
Ethylamine	5.6	
Diethanolamine	7.35	50
Water to make 100 cc.		

CO₂ is introduced until the solution has a pH value of 8.2.

What we claim is:

1. An aqueous solution for use in effecting the permanent deformation of hair and other keratinous material comprising a salt of a mercaptocarboxylic acid selected from the group consisting of thioglycollic acid and thiolactic acid with at least one organic base selected from the group consisting of guanidine, monoethylamine, monoethanolamine, diethanolamine, monoisopropanolamine and morpholine and a carbonate of said organic base, the pH value of the solution being from 7 to 9.

2. An aqueous solution for use in effecting the permanent deformation of hair and other keratinous material comprising a salt having a concentration of 0.3 to 1.5 mols per litre of a mercaptocarboxylic acid selected from the group consisting of thioglycollic acid and thiolactic acid with at least one organic base selected from the group consisting of guanidine, monoethylamine, monoethanolamine, diethanolamine, monoisopropanolamine and morpholine, and a carbonate of said organic base, the pH value of the solution being from 7 to 9.

3. An aqueous solution for use in effecting the permanent deformation of hair and other keratinous material

comprising a salt of mercaptocarboxylic acid selected from the group consisting of thioglycollic acid and thiolactic acid with at least one organic base selected from the group consisting of guanidine, monoethylamine, monoethanolamine, diethanolamine, monoisopropanolamine and morpholine, and a carbonate of said organic base having a concentration of 0.1 to 1.5 mols per litre, the pH value of the solution being from 7 to 9.

4. An aqueous solution for use in effecting the permanent deformation of hair and other keratinous material comprising a salt of a mercaptocarboxylic acid selected from the group consisting of thioglycollic acid and thiolactic acid with at least one organic base selected from the group consisting of guanidine, monoethylamine, monoethanolamine, diethanolamine, monoisopropanolamine and morpholine, and a carbonate of said organic base, the pH value of the solution being from 7.5 to 8.5.

5. An aqueous solution for effecting the permanent deformation of hair and other keratinous material comprising a salt having a concentration of 0.3 to 1.5 mols per litre of a mercaptocarboxylic acid selected from the group consisting of thioglycollic acid and thiolactic acid with at least one organic base selected from the group consisting of guanidine, monoethylamine, monoethanolamine, diethanolamine, monoisopropanolamine and morpholine and a carbonate of said organic base having a concentration of 0.1 to 1.5 mols per litre, the pH value of the solution being from 7.5 to 8.5.

6. A process for the preparation of an aqueous solution for effecting the permanent deformation of hair and other keratinous material comprising passing carbon dioxide into an aqueous solution containing a mercaptocarboxylic acid selected from the group consisting of thioglycollic acid and thiolactic acid and at least one organic base selected from the group consisting of guanidine, monoethylamine, monoethanolamine, diethanolamine, monoisopropanolamine and morpholine, until the solution attains a pH value from 7 to 9.

7. A process for the preparation of an aqueous solution for effecting the permanent deformation of hair and other keratinous material comprising passing carbon dioxide into an aqueous solution containing a mercaptocarboxylic acid selected from the group consisting of thioglycollic acid and thiolactic acid and at least one organic base selected from the group consisting of guanidine, monoethylamine, monoethanolamine, diethanolamine, monoisopropanolamine and morpholine until the solution attains a pH value from 7.5 to 8.5.

8. A method of imparting a permanent deformation to hair and other keratinous material which comprises constraining the material to a desired configuration, treating the constrained material at room temperature with an aqueous solution comprising a salt of a mercaptocarboxylic acid with at least one organic base selected from the group consisting of guanidine, monoethylamine, monoethanolamine, monoisopropanolamine and morpholine, and a carbonate of said organic base, the pH value of the solution being from 7 to 9, and thereafter setting the configuration of the material by oxidation.

9. An aqueous solution for use in effecting the permanent deformation of live human hair, comprising: a salt of a mercaptocarboxylic acid selected from the group consisting of thioglycollic acid and thiolactic acid with a mixture of guanidine and guanidine carbonate, the pH value of the solution being from 7 to 9.

10. An aqueous solution for use in effecting the permanent deformation of live human hair comprising: a salt of a mercaptocarboxylic acid selected from the group consisting of thioglycollic acid and thiolactic acid with a mixture of monoethylamine and monoethylamine carbonate, the pH value of the solution being from 7 to 9.

11. An aqueous solution for use in effecting the permanent deformation of live human hair, comprising: a salt of a mercaptocarboxylic acid selected from the group

consisting of thioglycollic acid and thiolactic acid with a mixture of monoethanolamine and monoethanolamine carbonate, the pH value of the solution being from 7 to 9.

12. An aqueous solution for use in effecting the permanent deformation of live human hair, comprising: a salt of a mercaptocarboxylic acid selected from the group consisting of thioglycollic acid and thiolactic acid with a mixture of diethanolamine and diethanolamine carbonate, the pH value of the solution being from 7 to 9.

13. An aqueous solution for use in effecting the permanent deformation of live human hair, comprising: a salt of a mercaptocarboxylic acid selected from the group consisting of thioglycollic acid and thiolactic acid with a mixture of monoisopropanolamine and monoisopropo-

nolamine carbonate, the pH value of the solution being from 7 to 9.

14. An aqueous solution for use in effecting the permanent deformation of live human hair, comprising: a salt of a mercaptocarboxylic acid selected from the group consisting of thioglycollic acid and thiolactic acid with a mixture of morpholine and morpholine carbonate, the pH value of the solution being from 7 to 9.
